UNITED STATES PATENT OFFICE

RAYMOND E. DE WALT, OF LEOLA, PENNSYLVANIA

FLOOR-SANDING MACHINE

Application filed July 31, 1926. Serial No. 126,169.

This invention relates to an electrically driven machine for surfacing, sanding or polishing floors, and aims to provide an easily portable machine of simple and efficient construction.

A feature of the invention resides in the utilization of an electric motor of the type in which the central core remains stationary and the outer shell revolves. This revolving motor shell is used as a pulley for moving the endless abrasive belt which passes over a second pulley and a suitably mounted idler. A movable presser plate, which is adapted to move the abrasive belt into contact with the floor surface to be treated, is controlled by a trigger in such a manner that the trigger may be manipulated to vary the pressure with which the belt is applied to the floor.

The invention also includes a power-driven fan for collecting the dust inevitably created by the surfacing mechanism.

Other features and objects of the invention will become apparent as the description proceeds.

While I have disclosed a preferred embodiment for purposes of illustration, it should be understood that various changes may be made without departing from the spirit and scope of the invention as hereinafter set forth and claimed.

In the drawings,

Fig. 1 is a side elevation of the machine, parts being broken away;

Fig. 2 is an elevation of the upper end of the handle;

Fig. 3 is a plan view, parts being broken away;

Fig. 4 is a detail plan of the presser plate;

Fig. 5 is a detailed elevation of the attachment of one side of the handle to the body of the machine.

Referring to the drawings more specifically, the body of the machine is composed of two side frames 10 between the rear ends of which the motor is mounted. The hollow

shaft 11 of the motor is non-rotatably secured to the side frames, and the conductors feeding current to the motor are led through the shaft as indicated in Fig. 3. The rotatable outer shell of the motor is of substantially the same height as the side frames, and acts as a pulley to support the rear end of the abrasive belt 13, which is of any suitable material coated with sand, carborundum, or other abrasive. The forward end of the drive belt passes around a roller 14 journaled between the forward ends of the side frames, while a spring-pressed idler 15 is provided for taking the slack out of belt 13. The idler is mounted on a carriage 16 pivoted on the shaft 17 and a coiled spring 18 surrounds the shaft and presses the idler upward against the under side of the belt.

A cross member 19 extends between the central part of the side frames and braces them in proper spaced relation. The lower edge of each side frame carries a hard wood runner 20, the runners being adapted to slide across the floor surface under treatment and to carry the weight of the forward part of the machine. Most of the weight of the motor is carried by two wheels 21 mounted at the rear of the side frames. Handle members 22 and 23 are attached to the side frames and provide means by which the machine is controlled, the motor switch 37 being mounted on the handle members.

The parts are so arranged that when the machine is in position on a floor surface, as in Fig. 1, the abrasive belt is parallel to the floor but is normally spaced therefrom. Means are provided by which the operator can move the belt into contact with the floor at will. These means include the presser plate 24 pivotally mounted on the arm 25 of a bell crank, the shaft 26 of which passes through a lug 27 depending from the cross member 19 and after extending through the side frame 10 carries an operating arm 28. A control rod 29 is attached to the outer end

of arm 28, extends along the handle member 22 and is connected to a trigger 30 pivoted below the hand piece 31. A flat spring 32 is mounted between the hand piece 31 and the trigger 30 and tends to normally hold the presser plate 24 in elevated position. By pressing the trigger toward the hand piece the operator can depress the presser plate, causing the belt to engage the floor, the 10 amount of pressure with which the belt engages the floor depending upon the amount of pressure applied to the trigger.

In order to collect the dust caused by the abrading mechanism, a sheet metal cover 33 15 closes the rear end of the machine and carries a motor-driven suction fan 34, the latter discharging into a collection bag 35. The cover 33 together with the runners 20 provides a dust-tight casing surrounding the 20 point of work and causes the dust to move in the direction of travel of the belt; i. e., toward the suction fan 34.

Whenever it becomes necessary to replace a worn belt or to change the character of the 25 abrading surface, the belt can readily be removed. To permit such removal the cover 33 is removably attached by a plurality of thumb screws 35 and the left handle can be separated at the hinge 36. After the cover 30 has been removed as shown in Fig. 5 the hinge 36 is opened and the belt can be slipped off on this side of the machine.

It will be noted that in the operation of the machine the runners 20 serve as bumpers 35 to keep the machine from marring the wood-work. The operator has complete and extremely sensitive control over the working pressure at all times and because of the large flat area of the pressure plate the machine 40 produces a floor area free from furrows or ridges.

I claim:

1. In a sanding machine, a pair of side frame plates, a motor roller between the 45 plates at the rear thereof, an idler roller between the plates at the front thereof, a presser plate between said plates intermediate of the lower parts of the rollers, a rock shaft extending across the device from one side 50 plate to the middle of the machine, a rock arm on the inner end of the rock shaft and pivotally connected to the presser plate at its center, a second rock arm on the outer end of the rock shaft, a handle projecting upwardly 55 from the side plate, an operating lever on said handle, a link connecting the second rock arm and lever, and a sander belt extending around said rolls and under said plate.

2. In a sanding machine, a pair of side 60 frame plates, a motor roller between the plates at the rear thereof, an idler roller between the plates at the front thereof, a presser plate between said plates intermediate of the lower parts of the rollers, a rock shaft 65 extending across the device from one side

plate to the middle of the machine, a rock arm on the inner end of the rock shaft and pivotally connected to the presser plate at its center, a second rock arm on the outer end of the rock shaft, a handle projecting upwardly from the side plate, an operating lever on said handle, a link connecting the second rock arm and lever, a sander belt extending around said rolls and under said plate, and means to maintain constant tension on said sander belt.

In testimony whereof I affix my signature.
RAYMOND E. DE WALT.
